UNITED STATES PATENT OFFICE.

ALFRED R. HUSSEY, OF HARVARD, MASSACHUSETTS, ASSIGNOR TO AMERICAN WATER SUPPLY OF NEW ENGLAND, OF BOSTON, MASSACHUSETTS, A CORPORATION OF MASSACHUSETTS.

VENDING-MACHINE.

1,026,166.

Specification of Letters Patent.

Patented May 14, 1912.

Original application filed January 25, 1909, Serial No. 474,021. Divided and this application filed December 27, 1910. Serial No. 599,464.

To all whom it may concern:

Be it known that I, ALFRED R. HUSSEY, residing at Harvard, in the county of Worcester and State of Massachusetts, have 5 invented an Improvement in Vending-Machines, of which the following is a specification.

This application is a division of my application for vending-machine #474,021, 10 filed January 25, 1909, and relates particularly to delivering-mechanism for drinking-cups, whereby the cups may be taken successively from a pile of nested cups and conveyed to a cup-support on which they 15 are disposed in upright position.

The invention has for its object improvements in the construction of the cup-delivering mechanism to the end that the cups may be taken successively from a pile and 20 conveyed to a position above a cup-support or table, their position being reversed in transit, and then released and permitted to fall by gravity onto said support, the releasing-means being operated automatically 25 as soon as the cups are brought into position above the support.

By my improvements the cup is automatically disposed on the cup-support, in upright position, within easy reach of the 30 operator.

Figure 1 is a front elevation of a vending-machine, having cup-delivering mechanism embodying this invention. Fig. 2 is a side elevation of the machine shown in 35 Fig. 1. Fig. 3 is an end view of the oscillating-member bearing the cup-receiver. Fig. 4 is a side view of the oscillating-member bearing the cup-receiver. Fig. 5 is a vertical section of the oscillating-member taken on the dotted line 5—5, Fig. 4. Fig. 6 is a sectional view similar to Fig. 5, the oscillating-member being inverted. Fig. 7 is a horizontal section of the oscillating-member taken on the dotted line 40 45 7—7, Fig. 6.

a represents a dome erected upon a hollow frame *a'* and having within it a chamber of suitable shape and size to receive a pile of cups, represented at *b*, Fig. 4, the 50 cups of said pile being inverted and nested together. The cups each have a lip *b'* at its upper end and they are successively removed from the pile by means provided for engaging the lips thereof. Within the hol-

low frame *a'* an oscillating-member is 55 placed which is adapted to remove a cup from the pile when turned in one direction, and to deliver a cup upon a cup-support when turned in the opposite direction.

The oscillating-member comprises essentially two disks or end plates *c*, *c'*, suitably spaced apart and joined together by a connecting portion *c''*. Said disks and connecting portions may be integrally formed if desired. The disks *c*, *c'* are arranged to fit 60 and turn freely in circular recesses formed in the interior of the hollow frame *a'*, being thus supported by said frame and free to oscillate therein. Said disks have arranged upon their inner or adjacent sides 65 suitable cup-engaging flanges *c''*, which are made substantially alike and oppositely disposed, and said flanges extend about half way around the disks, near the outer edges thereof. The inner sides of said disks are 70 also provided with bosses, as will be described, and said disks and the flanges and bosses thereon, are made alike or substantially so, hence one only need be described.

The flange *c''* is formed with a circular 75 outer edge, see Fig. 5, arranged concentric to the axis of the disk, and a circular inner edge arranged eccentric to said axis, so that said flange is pointed at one end and is made of gradually increasing width toward and 80 preferably to its opposite end. The boss *c''*, is arranged inside of the flange *c''*, and its outer edge is curved concentric to the inner edge of the flange, and it is disposed a short 85 distance from said flange, so that a groove 90 or way is provided between it and said flange. Said boss does not extend the entire length of the flange but from the point of the flange toward yet not to its opposite end. The end portion of the flange, opposite 95 its point, is made movable laterally but in an outward direction only, and, as here shown, said movable portion *c''* is hinged to the immovable portion, and the disk is 100 cut away to provide for such outward movement of said movable portion *c''*. The movable portion *c''* has on its outer side a finger 105 *c''*, which engages the interior of the frame *a'*, or a plate secured therein. As the disk oscillates, said movable portion is held in alignment with the immovable portion until it arrives at the end of the stroke, when said finger enters a cam-groove *c''* formed in the

frame, or plate therein, which acts to positively move outward said movable portion. Referring to Fig. 7 the frame a' is provided with a cam-groove c^7 for the finger on the movable portion on one of the disks, and a plate c^8 is rigidly secured to the frame a' which is provided with a cam-groove c^7 for the finger on the movable portion on the other disk.

10 The connecting-portion c^2 of the oscillating-member which is arranged between the two disks or end-supports is provided with a cup-receiver, which, as here shown, consists of a short tubular portion e rising from 15 said connecting-portion c^2 , and having several laterally extended wings e' , four being herein shown; and said wings are made tapering from end to end to thereby form a conical structure to receive upon it an inverted cup, as shown by dotted lines Fig. 5.

One of the disks, as c' , has connected with it a disk or plate f which fits a circular opening in one end of the frame a' , and which is provided with a hand-piece f' by which it 25 may be turned to oscillate the member. As here shown, said disk c' has a shouldered arbor c^{10} , which extends through a center-hole in the fixed plate c^8 and through a center-hole in the disk or plate f , and said disk 30 or plate f is secured to said arbor, thereby connecting said disk or plate f with the oscillating-member.

Normally the parts are in the position shown in Figs. 4 and 5, and at such time the 35 pile of cups rests upon the outer edges of the flanges c^3 on the disks c, c' , of the oscillating-member. As the oscillating-member is given a half turn in one direction by the hand-piece f' , as for instance, in a direction 40 toward the right, Fig. 5, its position is reversed, and the conical cup-receiver and other parts are moved into the position shown in Fig. 6, and when in this position the two movable portions c^5 of the flanges 45 are caused to swing outwardly, as represented in Fig. 7.

If a cup is reposing on the conical cup-receiver, as it should at such time, it will be free to fall by gravity upon a cup-support g , see Fig. 1, which is provided in the 50 frame of the machine beneath the oscillating-member, for it will be seen that the movable portions c^5 are swung outwardly so that the downward path of movement of the cup 55 is unobstructed, but unless said portions c^5 are swung outwardly the cup on the cup-receiver cannot pass to the cup-support by gravity alone. As the oscillating-member resumes its normal position the pointed ends 60 of the flange c^3 pass over the upper sides of the lip of the lowermost inverted cup of the pile, gradually withdrawing said cup therefrom as the lip follows along the groove or way which is provided between 65 the flanges and the bosses on the disks,

while the remaining cups of the pile rest on the outer edges of said flanges, and then as the cup-receiver resumes its upright position the inverted cup passes out of the groove or way and falls by gravity upon said receiver, preparatory to being delivered to the cup-support when the oscillating-member is again operated. Hence it will be seen that as the oscillating-member is moved in one direction the cup which reposes 70 on the cup-receiver will be delivered upon the cup-support and when moved in the opposite direction or returned to its normal position the lowermost cup of the pile will be taken therefrom and delivered to the cup-receiver. The particular novel features of 75 my invention consist in the movable portions c^5 , which provide for releasing the cup, permitting it to fall by gravity upon the cup-support, when but not until the cup has been turned into upright position, said movable portions thereby serving as releasing-devices for the cup; and also in the particular construction of the cup-receiver herein shown.

The other features of the machine thus far specifically described are not of my invention.

To return the oscillating-member to its normal position after it has been moved in 95 one direction by manipulating the hand-piece f' , a spring s is employed which is connected at one end to the frame-work and at the other end to a cylindrical frame j , see Figs. 2 and 3.

The disk c has a journal c^{12} , which has its bearings in a bar h , see Fig. 3, secured to the frame, and said bar is designed to serve as a limiting stop to limit the movement of the oscillating-member in both directions.

Attached to the disk c is a support for a water-scoop or dipper. Said support, as herein shown, is made as a hollow cylinder j , open at each end. It is attached to the 110 disk at its lower edge only, leaving an open space above said connecting portion for the bar h , and said connecting portion by striking against said bar limits the oscillating movement of the oscillating-member.

I claim:

1. In a vending machine wherein cups are successively taken from a pile and conveyed to a cup-support, the combination of means for supporting a pile of inverted 120 cups, an oscillating-member having means for removing the lowermost cup from the pile, and having a cup-receiver upon which the cup thus removed falls, and also having releasing-devices operating to release the cup 125 at the end of the stroke, permitting it to fall upon the cup-support, substantially as described.

2. In a vending machine wherein cups are taken from a pile and conveyed to a cup- 130

- support, the combination of means for supporting a pile of inverted cups, an oscillating-member having a cup-receiver and having tapering cup-engaging flanges provided 5 with outwardly movable end portions, and means for positively moving outward said end portions as the member bearing them is oscillated to permit the cup to fall upon the cup-support, substantially as described.
- 10 3. In a vending machine, the combination of a cup-support, an oscillating-member having a cup-receiver adapted to receive upon it an inverted cup and having releas-
- ing-devices for the cup, permitting it to fall from said receiver upon said support 15 by gravity, and means for oscillating said member and for operating said releasing-devices, substantially as described.
- In testimony whereof, I have signed my name to this specification in the presence of 20 two subscribing witnesses.

ALFRED R. HUSSEY.
